UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

BOX-MOTION-CONTROLLED ELECTROMAGNETIC WEFT DETECTOR.

Application filed December 30, 1924. Serial No. 758,904.

This invention relates to weft detectors for looms employing two or more shuttles and it is the principal object of the invention to provide a detector which shall be more 5 sensitive when detecting weft in certain shuttles than when detecting the weft in other shuttles.

In certain fancy fabrics it is frequently desirable to introduce occasional bands of 10 a very fine weft such as silk, the remainder of the fabric being woven of much coarser weft. Under such conditions if the usual type of feeler be adjusted for the very fine yarn it will not indicate substantial exhaustion of the coarser yarn until insufficient coarse yarn is present to lay the two picks usually required before transfer on automatic box looms.

In order to reduce the waste of both types 20 of yarn I have provided a detector, shown herein as being of the electromagnetic type, which can be rendered more or less sensitive according to the type of yarn in the active shuttle and it is accordingly a more detailed 25 object of my invention to provide a solenoid with a movable core to cooperate with a magnetic body in the shuttle, the strength of the solenoid being variable and under control of the box motion.

It is a further object of my invention to 30 provide an electro-magnetic weft detector having provision for causing a comparatively wide variation in the sensitiveness of the detector, this result being accomplished 35 by removable resistance units which can be substituted one for the other to vary the amount of current which is supplied to the solenoid.

It is a still further object of my invention 40 to provide a plurality of normally open electric circuits each including the detector combined with means to close the circuit corresponding to the active shuttle.

With these and other objects in view, 45 which will appear as the description proceeds, my invention resides in the combination and arrangement of parts hereinafter described and set forth in the claims.

In the accompanying drawings wherein I 50 have shown one embodiment of my invention,

Fig. 1 is a front elevation of the lower

portion of a loom having my invention applied thereto in connection with a box motion for two shuttles.

Fig. 2 is an enlarged end elevation of my improved detecting mechanism looking in the direction of arrow 2, Fig. 1,

Fig. 3 is a top plan view of the mechanism shown in Fig. 2,

Fig. 4 is a vertical section on line 4—4 of Fig. 1,

Fig. 5 is a vertical section on line 5—5 of Fig. 4,

Fig. 6 is a top plan view looking in the 65 direction of arrow 6, Fig. 4, and

Fig. 7 is a detail of one of the resistance elements, portions being in section.

Referring more particularly to the drawings it will be seen that I have provided a 70 loom frame 10 having associated therewith a box motion shown herein as adapted for two shuttles, the boxes 11 and 12, respectively, receiving the shuttles S and S' and being moved vertically by a box rod 13 75 which receives motion from any one of the approved box motions in common use. At the opposite end of the frame 10 is a magazine or weft replenishing mechanism indicated generally at 14 which may be of the 80 type shown in Patent No. 1,030,748 issued to Ryon, and having the bobbin selecting mechanism operated in part by link 15 which is movable vertically by a lever 16 to which it is pivoted. The central portion of the 85 lever 16 is connected to the vertically reciprocating rod 17 and the outer end of said lever is located to cooperate with the controller 18 to be described more in detail hereinafter. The controller 18 is normally out 90 of the path of the lever 16, to permit said lever to move downwardly without moving the link 15 but when the controller is under the lever the controller then becomes the pivot about which the lever moves and as 95 the latter is lowered link 15 will be depressed to actuate the magazine. The matter thus far described is of the usual construction and forms no part of my present invention.

My invention relates more particularly to the mechanism for actuating the controller 18 and consists of an electro-magnetic detector adjacent the magazine or the weft replenishing mechanism and a circuit maker

adjacent the box motion at the box end of the loom. The detector comprises a stand 30 bolted or otherwise secured to the loom frame 10 and having a horizontally extending shelf 31, an upstanding arm 32 and a forwardly projecting finger 33. Mounted upon the shelf 31 is a bracket 34 having spaced upright arms 35 which support a tube 36 which is formed of brass or any other suitable non-magnetic material. Surrounding said tube 36 is a solenoid 37 and passing through said tube is a core or plunger 38. Adjustably mounted on the core 38 is a collar 39 which confines a light compression spring 40 located between said collar and the adjacent arm 35. A holder 41 is also adjustably mounted on said core or plunger 38 and is provided with a hollow neck 42 which receives the lower bent end 20 of controller 18. Arm 32 is provided with a horizontal bore 43 through which the controller 18 extends and said arm is also provided with a vertical slot 44 in which moves the lever 16.

25 Finger 33 has projecting therefrom a stud 45 on which is loosely mounted a lever 46 having a depending arm 47 placed for engagement with the core or plunger 38 and limited in its rearward movement by adjusting screw 48 which passes through boss 49 on said finger 33. Projecting forwardly from the lever 46 is a second arm 50 which receives the upward end of a spring 51 the lower end of which is secured in finger 33. By means 30 of said spring 51 the arm 47 is held normally in rearward position against the adjusting screw 48. Said spring 51 is considerably stronger than the spring 40.

The magazine end of the lay is provided 40 with a single shuttle box which may be occupied by either shuttle S or S', shuttle S being shown therein in Fig. 2. Shuttle S has therein a bobbin W which is provided with a ferrule F of magnetic material, said ferrule 45 being placed as indicated in Fig. 3 so as to lie opposite the plunger or core 38 when the shuttle is in the single box. Each of the shuttles is provided with a bobbin having a ferrule F.

50 As previously stated the shuttles carry yarn of widely different characteristics and it is desirable that the solenoid 37 be relatively strong when detecting coarse yarn and relatively weak when detecting fine yarn. 55 The mechanism for effecting a change in the strength of the solenoid is located adjacent the box end of the loom. Referring more particularly to Figs. 4, 5, and 6 it will be seen that I have provided a block 52 having a split portion 53 by means of which the same may be held to the box rod 13 by clamping screws 54. Said block is preferably formed of insulating material and has extending therefrom an offset flange 55 which supports 60 contact block 56 by means of screws 57.

Held to the contact block 56 as by bolts 58 is a contact shoe support 59 also formed of insulating material. A contact shoe 60 is provided for the upper portion of the support 59 and another contact shoe 61 is provided for the lower part of the support 59, said contact shoes being insulated from each other and held in place by means of screws 62. The bolts 58 are preferably out of vertical alignment with the shoes 60 and 61.

70 75

The shoes cooperate with a relatively fixed contact plate 63 which is suitably held to a holder 64 of insulating material, said holder being mounted on an upright 65 which may be mounted on the picker foot P as shown in the drawings. Said contact plate 63 is so placed as to be in contact with one or the other of the shoes according to the position of the active shuttle box, vertical adjustment of the shoes being afforded by clamping screws 54.

In order to vary the strength of the current flowing through the solenoid 37 I have provided resistance units indicated generally at R and R', said units being shown in detail in Fig. 7 and comprising a base 66 having formed integral therewith a barrel 67, said base and barrel being formed of insulating material. A pair of split prongs 68 project from the base 66 and are electrically connected with the opposite ends of the resistance wire 69 which is wrapped around the barrel 67, one end of said wire 69 being led to the corresponding prong 68 through a bore 70 which passes through the base and barrel. Said prongs 68 are adapted to be received by contact openings 71 formed in the contact block 56 and contact openings 72 formed in the shoes, respectively.

90 95

100 105 Shuttle S is occupied by a bobbin wound with relatively coarse yarn while the shuttle S' is provided with relatively fine yarn and because of this fact a greater length of yarn can be wound on the bobbin in the shuttle S' than can be wound on the bobbin in the shuttle S. For this reason when a given length of yarn remains on the bobbin in shuttle S the diameter of said yarn will be larger than will be the case when the same length of yarn remains on the bobbin in shuttle S'. The amount of yarn remaining in the two shuttles when replenishment is desirable will therefore be of different diameters but the plunger 38 will be equally sensitive in both instances to indicate. Inasmuch as at indication for the coarse yarn it should be further from the metallic ferrule than with the fine yarn, it is necessary that the solenoid be relatively stronger for the coarse yarn and to accomplish this result a relatively light resistance will be in circuit when the coarse yarn is being woven. As shown in the drawings the resistance R will be small while the resistance R' will be large.

110 115

120 125 When the shuttle S is active the current 130

will start from the battery B, pass through wire 80 to contact plate 63, pass through shoe 60 and resistance element R, through contact block 56, through wire 81 to the solenoid 37 and from the solenoid back to the battery through wire 83. When the boxes change so that the relatively fine yarn becomes active with shuttle S' opposite the race, the rod 13 will be raised to bring contact plate 63 opposite shoe 61, in which case the circuit will be similar to that previously traced except that the current will pass through the resistance R' which is relatively large to lessen the attractive force of the solenoid and its core. In this way the amount of current flowing through the solenoid is varied according to the shuttle which is active, the solenoid being in each of a plurality of normally open circuits. As the yarn becomes depleted the distance between the rear end of the plunger 38 and the metallic ferrule grows less and less and when the desired amount is reached, depending upon the adjustment of collar 39, the attraction between the ferrule and the plunger will be sufficient to move said plunger rearwardly as the lay starts on its backward movement. Such a motion is accompanied by a movement of the controller under the lever 16 and as the latter descends an operative movement is given to the magazine as previously described.

A wire or other projection 84 extends from the collar 39 to be engaged by the transfer mechanism to withdraw the feeler, an operation well understood in the art. The upright 65 is pivoted as at 85 to the picker foot P and is held normally toward the contact block by coiled spring 86. From the foregoing it will be seen that I have provided a single detector for cooperation with a plurality of shuttles and have provided for rendering said detector sensitive to any selected degree to agree with the active shuttle. If fine yarn is being detected the attraction between the plunger and the ferrule will be relatively low so as to cause a backward movement of the plunger when a comparatively thin layer of yarn is present but if coarse yarn is being woven requiring a greater thickness of yarn at the time of indication then the attraction between the ferrule and the plunger will be stronger. It will also be noted that I have provided resistance units which can be changed easily, thus imposing no limitation upon which of the boxes shall occupy the shuttle supplied with fine yarn. Also, it will be seen that the detector is in each of a plurality of normally open circuits which are closed, one at a time, in timed relation with the active shuttle. Although I have shown the invention as applied to a two box loom, the principles set forth herein can be extended to cover more boxes and I do not

wish to be limited to the construction shown herein as I believe the device set forth herein is the first electro-magnetic weft detector which is sensitive in varying degrees according to which shuttle is active. 70

Having thus described my invention it will be apparent that changes and modifications may be made therein by those skilled in the art without departing from the spirit and scope of the invention, and I do not wish to be limited to the details herein disclosed, but what I claim is:

1. In a loom, shifting shuttle boxes, an electro-magnetic weft detector, and means controlled by the position of the shuttle boxes to render the magnetic attraction of said detector greater when said boxes are in one position than when they are in another position. 80

2. In a loom, a plurality of shifting shuttle boxes, means to move said boxes to a plurality of positions, an electro-magnetic weft detector, and means under control of the first named means to vary the magnetic attractive force of the detector. 85

3. In a loom, an electro-magnetic weft detector, shifting shuttle boxes each of which may move to active position, a plurality of resistance units each different in value from the other movable with the boxes, and means to connect said detector in circuit with any one of said resistances. 90

4. In a loom, an electro-magnetic weft detector, shifting shuttle boxes each of which may move to active position, a plurality of resistance units each different in value from the other and movable with the boxes, and means to establish a plurality of circuits each of which contains the detector and one of the resistances. 100

5. In a loom having a plurality of shifting shuttle boxes and shuttles each carrying a magnetic body and each of which may become active one at a time, an electro-magnetic detector to cooperate with each shuttle when active, a plurality of normally open electric circuits each including said detector, a plurality of removable resistance units of different values, each circuit including a removable resistance unit, and means dependent upon which shuttle box is in active position, to close but one of said circuits at a time. 110

6. In a loom, shifting shuttle boxes, sliding contacts movable therewith, removable resistance units movable with the boxes and contacts, an electro-magnetic detector, and means to establish a plurality of circuits each including said detector and one of the contacts and one of the movable resistance units. 120

7. In a loom, a plurality of shifting shuttle boxes, a plurality of contacts movable with the boxes, a plurality of interchangeable resistance units of different values mov- 130

able with the boxes, an electro-magnetic detector, and means to establish a plurality of electric circuits each including the detector and one of the interchangeable resistance units.

8. In a loom having a plurality of shuttles each provided with a magnetic body, shifting shuttle boxes to move the shuttles one at a time to active position, an electro-magnetic detector, a supporting structure, a plurality of interchangeable resistance units mounted on said supporting structure, a plurality of circuits each to include said detector and one of the resistance units, and means dependent upon the position of the shuttle boxes to close one or another of said circuits at a time.

9. In a loom, a plurality of shifting shuttle boxes and shuttles therefor, an electro-magnetic weft detector to cooperate with anyone of the shuttles one at a time, a magnetic body carried by each shuttle, means to cause magnetic attraction between the detector and magnetic body of the shuttle being detected, and means dependent upon which shuttle box is in active position to vary said attraction.

10. In a loom, a plurality of shifting shuttle boxes and shuttles therefor, an electro-magnetic weft detector to cooperate with anyone of the shuttles which may become active, a magnetic body carried by each shuttle, means to cause magnetic attraction between the detector and the magnetic body carried by the active shuttle, and means dependent upon which shuttle box is in active position to vary said attraction in timed relation with the movements of the shifting shuttle boxes.

11. In an electro-magnetic detector to cooperate with a plurality of shuttles in a loom having shifting shuttle boxes and wherein each shuttle is provided with a magnetic element, a magnetized element forming part of said detector and means dependent upon which shuttle box is in active posi-

tion to vary the degree of magnetization of said magnetized elements.

12. In a loom, a plurality of shuttle boxes and shuttles therefor, each shuttle having a body of magnetic material, a magnetized detector to cooperate with the bodies of magnetic material of each of the shuttles, and means dependent upon which shuttle box is in active position to vary the degree of magnetization of said magnetized body.

13. In a loom having a plurality of shifting shuttle boxes and shuttles therefor, each shuttle being provided with a magnetic element, a weft detector having a magnetized element, and means dependent upon which shuttle box is in active position to vary the attracted force between said elements.

14. In a loom having a plurality of shuttle boxes and shuttles therefor each of which may become active, an electro-magnetic weft detector, and means dependent upon which shuttle box is in active position to vary the strength of the current energizing said electro-magnetic weft detector.

15. In a box loom having a plurality of shuttle boxes and shuttles therefor each of which may become active, a solenoid, a plurality of resistances of different values, means dependent upon which shuttle box is in active position to connect said solenoid electrically with one or another of said resistances, and weft detecting mechanism operatively associated with said solenoid.

16. In a loom having a plurality of shifting shuttle boxes and shuttles therefor each of which may become active, an electro-magnetic detector to cooperate with each shuttle when active, and means coordinated with the shuttle boxes and dependent upon which shuttle box is in active position to vary the strength of the electric current energizing said electro-magnetic detector.

In testimony whereof I have hereunto affixed my signature.

WALTER H. WAKEFIELD.
